UNITED STATES PATENT OFFICE.

CHARLES O. ALLEN, OF SHAWNEE, OKLAHOMA.

SWIVEL CONNECTION FOR ELECTRICAL CONDUCTORS.

1,379,795.

Specification of Letters Patent. Patented May 31, 1921.

Application filed April 9, 1919. Serial No. 288,754.

To all whom it may concern:

Be it known that I, CHARLES O. ALLEN, a citizen of the United States, residing at Shawnee, in the county of Pottawatomie and State of Oklahoma, have invented certain new and useful Improvements in Swivel Connections for Electrical Conductors, of which the following is a specification.

My invention relates to improvements in swivel connections for electrical conductors, and it consists in the combinations, constructions and arrangements herein described and claimed.

An object of my invention is to provide a swivel connection which will prevent the twisting of electrical conductors, especially those used in connection with telephone sets.

A further object of my invention is to provide a swivel connection which may be readily applied to a telephone box, and which will positively prevent the cord which leads to the telephone set from becoming twisted.

A further object of my invention is to provide a device of the type described which is simple in construction has few parts, and which is therefore not liable to easily get out of order.

Other objects and advantages will appear in the following specification, and the novel features of the invention will be particularly pointed out in the appended claims.

My invention is illustrated in the accompanying drawings, forming part of this application, in which:

Figure 1 is a section through a telephone box, showing my improved swivel connection in position;

Fig. 2 is a plan view of the device, the cover or cap being removed;

Fig. 3 is a section along the line 3—3 of Fig. 2;

Fig. 4 is a plan view of the main body portion of the device, a part being shown in section, and

Fig. 5 is an end view of the auxiliary contact bearing member.

Referring now particularly to Fig. 3, I have shown therein a main body portion 1, which may be made of wood, metal, hard rubber or any other suitable insulating material. This body portion is preferably of cylindrical shape, and has a cylindrical extension 2, which is designed to enter and be retained in the opening 3, of the telephone box 4, see Fig. 1. The body portion

1 has a central recess extending inwardly from the end opposite the extension 2, and is provided with a series of shoulders in stepped relation bordering the recess and each having a conducting member thereon, such as a copper ring, these members being shown at 5, 6 and 7 respectively. Each ring has an electrically conducting connection with a terminal on the outer surface of the body portion, as shown at 5^a, 6^a and 7^a, respectively.

In Fig. 5 I have shown an auxiliary contact-bearing member 8, of cylindrical shape, and having a series of shoulders corresponding to the shoulders of the body portion, each shoulder being provided with a ring-shaped contact arranged to engage the contacts on the body portion. I prefer to make these contacts of spring wire, although it is obvious that other forms of contacts might be used without departing from the invention. In Fig. 5, the contacts which are carried by the auxiliary contact-bearing member 8, are designated 5^x, 6^x and 7^x, and they are arranged to engage the respective contacts 5, 6, and 7 when the parts are assembled. The body portion is provided with a central recess or bore 9, arranged to receive the extension 10, of the contact-bearing member 8. One end of each of the contact members 5^x, 6^x is free, the opposite end being passed through grooves, such as those shown at 11, and being secured to the three strands of the cord or cable 12, which passes through a central bore in the member 8, as clearly shown in Fig. 3.

From the foregoing description of the various parts of the device, the operation thereof may be readily understood. As has been heretofore stated, the device illustrated is primarily designed to be used with telephone boxes. The wires 14 from the coils in the interior of the box, are connected with the terminals 5^a, 6^a and 7^a in the manner shown. The auxiliary contact-bearing member 8 fits into the central recess of the body portion 1, and the contacts 5^x, 6^x and 7^x engage the contacts 5, 6 and 7 while at the same time the auxiliary contact-bearing member 8 is permitted to rotate about its central axis. Now the telephone cord 12, where it passes through the member 8, has its axis coincident with the member 8. A cover 15 is provided, and it may be held on frictionally or in any other suitable manner.

The construction described above prevents

any twisting or kinking of the cord. The contacts 5^x, 6^x and 7^x have just enough spring in them to permit good contact to be made in any position of the auxiliary contact-bearing member. If the cord should have any tendency to twist, then the member 8 will rotate about its central axis, but it will keep the contacts in engagement electrically while so doing. The construction is such that the cord may be turned either way and the member 8 will rotate in either direction. The cover 15, besides holding the auxiliary member 8 in position, to effect a good electrical connection, keeps the dust or dirt from interfering with the proper working of the device.

While I have described this electrical connection as being primarily adapted for telephone boxes, it is obvious that it might be used for other purposes such as electric irons or electric utensils of any kind, without departing from the spirit and the scope of the invention.

I claim:

1. A swivel connection for electrical conductors comprising a body portion having a central recess and being provided with a plurality of shoulders in stepped relation bordering said recess, a contact ring carried by each shoulder, an auxiliary contact-bearing member having a plurality of shoulders,

a contact carried on each shoulder of said auxiliary contact-bearing member, said auxiliary contact-bearing member being arranged to enter the recess of said body portion to bring its respective contacts into engagement with the rings of the body portion, a cap for retaining said auxiliary contact-bearing member in its operative position, the contacts of said auxiliary contact-bearing member being secured to the strands of an electrical conductor.

2. In a swivel connection for electrical conductors a body portion having a recess and being provided with a series of shoulders in stepped relation bordering said recess, a ring-shaped conductor mounted on each shoulder and having an electrical connection extending to the side of the body portion, an auxiliary contact-bearing member having contacts arranged to engage the contacts on the body portion, said auxiliary contact-bearing member having a central bore arranged to receive a cable and the strands of the cable being connected to the respective contacts of the auxiliary contact-bearing portion, and a cap for covering the recess in the body portion and for retaining the auxiliary contact-bearing member in its operative position.

In testimony whereof I affix my signature.

CHARLES O. ALLEN.
